RAILWAY CAR BODY

Alfred C. Lohse, Michigan City, Ind., and William H. Mussey, Chicago, Ill., assignors to Pullman-Standard Car Manufacturing Company, Chicago, Ill., a corporation of Delaware

Application March 29, 1937, Serial No. 133,632

3 Claims. (Cl. 105—404)

This invention relates to railway cars.

One of the objects of the invention is the provision of a new and improved car construction having novel arrangements of parts whereby the car has a minimum weight and maximum capacity.

Another object of the invention is the provision of new and improved end and side posts for the car body.

A further object of the invention is the provision of a new and improved outside sheathing for the sides of the car, so constructed and arranged that the edges of certain of the plates are overlapped and interengaged and certain of the edges are pressed to form side posts.

Another object of the invention is the provision of a new and improved structure including car lines integral with certain of the roofing sheets.

Another object of the invention is the provision of a new and improved method of fabricating the parts of the car by extensive electric welding and assembling the fabricated parts.

A still further object is the provision of a new and improved car that is light in weight, rigid in construction, that may be fabricated in horizontal position in separate units by extensive welding, and the units assembled with a minimum of time and expense.

Other and further objects and advantages of the invention will appear from the following description taken in connection with the accompanying drawings in which—

Fig. 1 is a top plan view of a railway car embodying the invention, with parts broken away;

Fig. 2 is a side elevation, with parts broken away;

Fig. 3 is a perspective view of the subframe at one end of the car showing the side end sills and reinforcing members in position but omitting the side and end walls for the sake of clearness;

Fig. 4 is a vertical transverse section of a portion of the bolster showing the closure plate in position;

Fig. 5 is a perspective view of one end of the vehicle showing the structure partially assembled, the side walls being in position on the subframe and the end walls being in position to be attached to the center sill, side sills and end wall;

Fig. 6 is an end elevation of the car, with one-half in cross-section, and with parts broken away;

Fig. 7 is a section on the line 1—1 of Fig. 6;

Fig. 7a is a section on the line 7a—7a of Fig. 6;

Fig. 8 is a section on the line 8—8 of Fig. 6 on an enlarged scale, with parts broken away and parts omitted for the sake of clearness;

Fig. 9 is a horizontal section of one corner of the car and a portion of the end thereof, showing a modified corner post construction, with parts broken away;

5 Fig. 10 is a vertical section of one side of the car through the door, with parts broken away;

Fig. 11 is a vertical section through an end of the car, with parts broken away;

Fig. 12 is a section on the line 12—12 of Fig. 2, 10 with parts broken away;

Fig. 13 is a side elevation thereof, with parts broken away;

Fig. 14 is a section on the line 14—14 of Fig. 2, with parts broken away;

15 Fig. 15 is a side elevation of the structure shown in Fig. 14, with parts broken away;

Fig. 16 is a horizontal section across one corner and a portion of the side, with parts broken away, but showing a modified form of corner post construction;

Fig. 17 is a side elevation of the structure shown in Fig. 16, with parts broken away;

Fig. 18 is a horizontal section across one of the corners of the car showing a modified form of construction;

25 Fig. 19 is a similar view showing another modified form;

Fig. 20 is a view similar to Fig. 18 showing a still further modified form of construction;

30 Fig. 21 is a horizontal section of one of the end posts and a portion of the car structure showing a modified form of construction;

Figs. 22, 23, 24 and 25 are vertical sections of a side plate and associated parts showing 35 modified forms of the construction shown in Fig. 10;

Fig. 26 is a cross section of a portion of the eaves of the car roof showing the same in perspective, with parts broken away;

40 Fig. 27 is a vertical section adjacent one of the side posts showing a modified form of attaching the side posts to the side sill, with parts broken away;

Fig. 28 is a side elevation of the structure shown 45 in Fig. 27;

Fig. 29 is a section similar to Fig. 27 but showing a modified form of construction; and

Fig. 30 is a side elevation thereof.

In the construction of railway cars, it is desirable that the weight of the car be greatly reduced from that of the conventional car without altering its outside dimensions or decreasing its capacity.

The present invention seeks to materially reduce the weight of car body underframe and

truck structure by the employment of sheet metal or sheet steel and the extensive use of welding. It has been found that with the use of sheet metal or sheet steel, the weight of the completed car may be reduced as much as 30% or even more and that the capacity may even be somewhat increased without sacrificing any of the strength or sturdiness of the conventional car. This material reduction in the weight results from the use of sheet steel from .05 inch to $\frac{1}{8}$ inch in thickness, pressed to form and welded in position, thus eliminating, to a very great extent, the use of commercial rolled angle and channel irons or bars.

Referring now to the drawings, the reference character 1 designates generally a railway car having the underframing 2, Figs. 1 to 4, supported by the trucks 3, side walls 4, end walls 5, flooring 6 and roof section 7.

The underframing comprises the center sill 8, Figs. 2, 3 and 5, bolsters 9, cross bearers 10 and floor supports 11. The angle member 12 and subframe or subsill 13 are considered as a part of the side wall of the car since they are rigidly connected to the side sills which in turn are rigidly connected to the side walls as will presently appear.

Referring now to Fig. 3, which shows only a portion of one end of a car with the side and end sheathing removed for the sake of clearness, the side and end sills are rigidly connected to the underframe as they will occur when the car is completed, the center sill 8 is composed of two Z-bars 14 and 15, Fig. 3, each having its upper flange turned inward and arc-welded together as at 16 throughout the length of the sill. The upper flange of each Z-bar is wider than the lower as shown in Fig. 3. Each end of the center sill is provided with a built up striker plate 17 comprising side plate members 18 and 19 welded to the ends of the center sill. A channel member 21 having slots on its ends for receiving the inner edges of the plates 18 and 19 is welded in position to the plates and to the webs of the Z-bars to form the coupler supporting portion of the striker plate 17. A wear plate 22 is welded in position on the channel member 21 and to the plates 18 and 19 and the webs of the Z-bars, as shown at 23. The upper portion of the striker plate comprises a curved plate 24, the upper edge of which is welded to the upper portion of the center sill and also overlaps the plates 18 and 19 and is welded thereto as at 25, Fig. 3. This plate extends downward and then inward and diagonally upward and is welded as at 26 to the under side of the upper flanges of the Z-bars to form a reinforcement for the striker plate.

The bolsters 9 at each end of the car are alike so only one need be shown and described. As shown in Fig. 3, the bolster is a boxlike structure of pressed sheet-metal and is composed of two sections, one at each side of the center sill, as shown in Fig. 5 which shows the end wall about ready to be slid in position on the center sill. Each section is a channel comprising the web portion 27 on, which for convenience of description will be termed, its forward side, extending outwardly laterally from the center sill. The upper and lower flanges 28 and 29 of this bolster section taper in width outwardly rearward from the center sill. The bottom flange tapers upwardly from the center sill outward forming a reduced end 31 which seats in an angle member 12 which in turn has the upper edge of its vertical flange arc-welded to the side sill as at 33.

The horizontal portion 133 of the side sill is welded to the bolster as at 330.

The top flanges 28 of the bolster sections are flush with the top of the center sill and the bottom flange is cut away to form a recess for receiving the lower flange 30 of the center sill as shown in Fig. 3. The bolster sections abut the center sill and are butt-welded thereto. In order to reinforce each of the bolster sections, each has a reinforcing member such as a Z-bar secured to the inner side of each of its flanges. The upper reinforcing Z-bar 37 extends from the center sill to a point adjacent the end of the bolster section, Fig. 6, while the lower one is in two sections 38 and 39. The section 38 is secured at its inner end to the lower flange 30 of the center sill, Fig. 3. The outer end of the section 38 engages a side of the inverted U-shaped brace 41 that extends parallel with the center sill for transversely bracing the bolster over the side bearing. The brace member 41 rests on the lower flange 29 of the bolster section and is welded thereto and is also welded at its forward end to the web 27 of the bolster. The rear end of the brace member 41 is welded to a small plate 42, see Figs. 3 and 4, which in turn is welded to the closure plate 43 as will presently appear.

The other section 39 of the bolster brace member has its outer end extending outwardly to a point adjacent to the bolster end and is secured to the lower flange 29 of the bolster section in any suitable manner as by being welded thereto.

A suitable reinforcing plate 430 extends across the brace member 41 in alinement with the sections 38 and 39 of the lower brace member and is secured to the lower flange 29 of the bolster and at its ends to the side walls of the brace member 41.

In the construction of the bolster section, the sheet from which the U-shaped section is made is bent to form, after which the brace members 37, 38, 39 and 41 are secured in position in the bolster member. The plate 42 is secured in position across the end of the U-brace 41 and a built up side bearing 44 is secured to the underside of the flange 29 of the bolster directly beneath the brace member 41.

After the longitudinal and transverse brace members are placed in position in the bolster section, a closure plate 43 is welded to the rear edge of the flanges 28 and 29 to complete the box structure. This closure member 43 is arc-welded as at 46 and 47 to the rear edges of the flanges 28 and 29 as shown more clearly in Fig. 4 of the drawings. The closure 43 is also secured to the plate 42 in any suitable manner as by welding which may be accomplished by providing openings in the plate 43 opposite the plate 42 and depositing welding metal 48 therein, Fig. 4.

After the bolster sections have been fabricated, they are secured to the center sill by being arc-welded on the four sides thereof to the center sill as shown at 49. This weld extends around the bolster section. The lower inner portion of the bolster is cut away to form a notch to conform to the flange 30 to which the parts are welded and on which the inner ends of the bolster sections are seated as shown in Fig. 3.

The cross-bearers 10 may be of any suitable construction. In the form of the construction shown, they are composed of split commercial eye beams, a section 51 at one side of the center sill and a similar section 52 at the other side. These beams are split from their inner ends and

the split ends are spread apart as shown in Fig. 3. Since these two sections are identical, only one will be described.

The upper portion 53 of each section is flush with the upper surface of the center sill and is welded thereto and extends at right angle therefrom as shown at 54, Fig. 3. The lower section 50 of the eye beam is cut to conform to the flange 30 and is welded thereto as indicated at 55. A suitable tension member, such as the U-bar 56, has its ends welded to the lower flange 51 of the lower section of the cross-beamer and extends beneath the center sill and has its opposite end welded to the lower section of the cross-beamer member 51 at the other side of the center sill. In order to reinforce the cross-beamer sections, a plate 58 is welded to each web section of the cross-beamer as shown in Fig. 3. Suitable braces or floor stringers 59 are attached to and extend between the bolster and cross-beamer sections at each side of the center sill as shown more clearly in Fig. 3. These floor stringers may be of any suitable form or shape but in the form shown, they are Z-bars and are supported flush with the upper surfaces of the bolster and cross-beamers by suitable hanger clips or Z-shaped plates 61 which are welded to the floor stringers 59 at the lower ends and to the bolster and cross beams at their upper ends.

A plurality of floor stringers 62 and 63 are attached to and extend rearwardly from each of the cross bearer sections as shown in Fig. 3.

Suitable braces or tension members 64 are provided for reinforcing the connection between the bolster sections and the center sills. Each of these members is angular in cross section and triangular in form and is cut to seat in the angle formed by the bolster and center sill and is welded to these members in such a position that the upper flange is flush with the upper surface of the bolster and center sill. It will be noted that on buff from the end shown in Fig. 3 these members will be placed under tension instead of compression, hence they may be of sheet metal which is a material saving in the weight of these members.

Suitable fillets 65 are provided between the angle formed by the bolster and the center sill at each side of the latter on the forward side of the bolster as shown in Fig. 3.

In the construction of the car, the end and side walls, together with the corresponding sills, are fabricated separately on horizontal jigs, after which these walls are assembled on the under-frame.

The end sills are built rigid with the end wall and afterward placed in position and arc-welded to the center and side sills. The end sills will now be described as they appear on the completed car and since they are substantially alike, only one is shown and described. Each end sill 66, may, if desired, be pressed to form or it may be of commercial angle iron and comprises two similar sections 67 which are adapted to be welded to each side of the center sill with the lower horizontal flange 68 of each flush with the top of the center sill. The outer end of each end sill section has its horizontal flange 68 cut away for receiving the end of the side sill to which it is rigidly secured as by welding as shown at 71 in Fig. 3.

Each end sill section 67 is provided with a sill extension or auxiliary end sill 72 which is angular in cross-section and has its horizontal flange 73 welded to the horizontal flange of the end sill 75

as shown in Fig. 3, and to the center sill as at 74. The vertical flange extends downward and is welded at its inner end to the center sill. Suitable triangular reinforcing plates 75 are welded to the horizontal flanges of the end sill and auxiliary sill member and to the vertical flange of the auxiliary sill member 72, Fig. 3. A suitable sheet metal tension member 76, which may be angular in cross-section and triangular in form, is welded in position in the corner formed by the center and auxiliary end sills as shown in Fig. 3. The vertical flanges 77 of the end sills are connected together by a plate 78 welded to these flanges and flush therewith. The end sill is made in two sections merely for the sake of convenience. The sill could have had the lower flange at its central portion for forming a notch for receiving the center sill, if desired. Reinforcing and brake rigging supporting elements 79 are provided beneath each end sill section. These members are preferably also of sheet metal and welded in position.

Each of the end sections comprises an end sill 66 having the auxiliary or sill extension 72, Fig. 11. The end sill 66 is pressed to form and is angular in cross-section having the upwardly extending flange 77 and an inwardly horizontally extending flange 68 in alignment with the horizontal flange 73 of the sill extension 72 as described above. Attached to and extending upwardly from the end sill 66 are a plurality of end posts comprising the outer posts 87 and intermediate posts 81 and corner posts 88, Figs. 6, 7, 9 and 11. Each end post is channel shaped in cross-section and has its side edges turned outwardly to form feet 89, Figs. 8 and 9. These feet are adapted to be attached to the end sheathing as by being welded thereto as indicated by the arrows in Fig. 9. The lower ends of the feet 89 are secured to the vertical flanges 85 of the end sill 66 as by being welded thereto, Fig. 11. Gussets 82, Fig. 11, may be provided across the flanges of the end sill for strengthening the same. The lower ends of the end posts are offset inwardly as shown at 91, Fig. 11, to accommodate the flange 77. The upper ends of the end posts each has its web portion 93 extending upwardly alongside the end plate 83, Fig. 11, and is rigidly secured thereto as by welding. The flange portions of the intermediate end posts are bent laterally outwardly as shown at 94, Figs. 6 and 11, beneath the horizontal portion 95 of the end plate 83 and are welded thereto.

The outer and intermediate end posts are preferably provided with reinforcing members 96 and 97, respectively. The intermediate portions of these reinforcing members are in the form of an angular U in cross-section as shown more clearly in Fig. 8, each having the outer edges of its flanges parallel with and welded to the side flanges of the end posts as shown at 98, Fig. 9. Each has a pair of flat portions 99 extending across the corners of the corresponding U-shaped end post for reinforcing the same, and a flat web portion 101 which engages and is welded to the corresponding web portion of the U-shaped end post. These reinforcing members may be considered as being channel members with angular flanges. The angular form of the reinforcing member 96 extends, as shown in Fig. 6, from the dotted line 102 to the dotted line 103 on the end post 87, Fig. 7. Above this point, the reinforcing member gradually takes the form of the post 81 and below the dotted line 103, the flanges of the reinforcing member are tapered

downwardly and the lower end of the reinforcing member is turned inwardly with its web portion extending beneath the floor 6 and is welded to the end sill extension 72 as at 104, Fig. 11, the floor 6 being provided with a slot 105 for accommodating the lower end portion of this reinforcing member. The reinforcing members in the intermediate end posts 81 are shaped similar to that of the post 87 having the angular portion between the dotted lines 106 and 107, Fig. 6, each with its upper end extending above the post 87 and terminating at the dotted line 108. The lower end of the reinforcing member 97 of the post 81 is attached to the end sill extension 72 in the manner just described.

Suitable reinforcing means may be provided for the posts 81 and their reinforcement members 97. In the form shown, a plate 109 having its edges welded to the sides of the post 81 and to the edges of the reinforcing member 97, for each post, is provided. This plate extends between the points 106 and 107, Fig. 6.

The top end plate 83 is angular in cross-section having the vertical portion 100, Fig. 11, the horizontal portion 95 and an outwardly offset vertical portion or flange 111. Suitable gussets of any appropriate form are provided between the vertical portion 100 and horizontal portion 95 of the end plate. In the form of the construction shown, gussets 112 may be in the form of channels, Fig. 6, and are preferably located above the central end posts 81. These gussets are triangular in shape, having a base substantially the same width as the horizontal portion 95 of the end plate to which they are rigidly connected as by being welded thereto. The flanges of these channel members are turned laterally outwardly to form feet 84 that are welded to the vertical portion 100 of the end plate 23. The upper edge or flange 110 of the end plate extends horizontally over the upper narrow end of the gusset plates and is welded thereto.

The corner posts 88, Figs. 6 and 9, each comprises a pressed angular member of sheet metal having a flange 113 extending parallel with the side wall of the car and a laterally extending flange 114. The lower ends of these flanges are secured to the side and end sills in any suitable manner as by rivets or welding. They are preferably welded to the end sills. Each of the posts is provided with a reinforcing member 115 of special form in cross-section. As shown more clearly in Fig. 9, this member extends substantially the entire length of the post and comprises what may be termed a straight web portion 116 extending across the angle formed by the flanges 113 and 114 and having short flat portions 117 and 118 extending parallel with the side and end walls, respectively, and rigidly secured to those walls by welding or rivets. The free edges of the reinforcing member extend inwardly in planes at right angles to the side and end walls, respectively, as shown at 119 and 121 and then outwardly at right angles to each other to form attaching feet 122 and 123 and form right angles with said inwardly extending portions within which are secured the wooden filler members or purlines 124 and 125.

The end sheathing comprises a plurality of vertically extending sheet metal plates. As shown, there are two outer sheets or plates 126, one attached to each corner post, an intermediate or central plate 127 and two connector plates 128, Fig. 9, one at each side of the center plate. The central or intermediate sheet 127 is attached

to the intermediate end posts 81 and overlaps the inner flanges of the outer end posts 87 and are welded thereto. The two outer sheets 126 are attached to the corner posts and to the outer flange of the outer end posts 87. The outer and intermediate plates or sheets are connected together by the connector plates or strips 128 which overlap the adjacent ends of the plates 126 and 127 as shown more clearly in Fig. 8 and are welded at the overlapping portions to the outer and intermediate plates. If desired, the strips or plates 128 may be thicker than the sheets 126 and 127 thereby adding rigidity to the end sheathing. The outer edges of the outer sheets 126 are each inserted between the flange 114 of the corner post and the straight portion or foot 118 of the reinforcing member 115 and is rigidly secured thereto as by welding, Fig. 9. The flange portion 111 of the end plate overlaps the upper ends of the end sheathing plates, Fig. 11, and is welded thereto. The connector plates 128 are foreshortened and have their ends welded to the lower edge of this flange 111, Fig. 6.

In fabricating the end wall, the corner posts, 25 end posts, end sill, end sill extension, end plate and outer end sheathing are first assembled in horizontal position on suitable jigs, as will presently appear.

Suitable inner sheathing 131 and the wooden 30 filler members or furlings 125 are preferably, though not necessarily, attached to the end wall after the frame structure of the car has been erected on the underframe.

The side walls of the car, each comprises a 35 side sill 90 and a side plate 132, Figs. 6 and 10. The side sills are angular in cross-section having the horizontal flange 133 and the vertical flange 134 extending throughout the length of the car. The side plates 132 are channel form in cross-section at their upper portion and have downwardly extending flanges 135. The channel faces outwardly and the upper flange 136 is of reduced width as shown more clearly in Fig. 10.

The side posts for the car are Z-shaped in 45 cross-section and are formed from the edges of the sheathing plates reinforced by suitable means as will now be described. The outer side sheathing is composed of a plurality of vertically arranged intermediate and outer sheet metal plates

50 137 and 1370, respectively. Each of the plates 137 has one edge offset inwardly slightly as at 138, Fig. 16, for forming a recess for receiving the adjacent straight edge 139 of an adjoining plate as shown in Figs. 1 and 16. The edge is then bent 55 to angular shape to form the web 137a and an offset flange 137b which together with the offset portion 138 forms an angular post 141, Z-shaped in cross-section, having an inner flange 137b extending longitudinally of the vehicle and adapted to contact the inner sheathing of the car and be welded thereto. Suitable means are provided for reinforcing the side posts 141. In the form of the device selected to illustrate one embodiment 60 of the invention, an angle bar 142, which is nested in the inner angle of the side post formed by the web 137a and flange 137b and welded thereto, is employed for this purpose for each of the posts. The outer sheets 1370 at the ends of the side walls 65 do not have either of their edges distorted. The outer edge of each sheet 1370 is secured between the adjacent flange of the corner post and the reinforcing member and its opposite edge 139 is secured in the offset 138 of the adjacent sheet or plate. The plates 137 and 1370 are arranged in 70 75

reverse order at each side of the door as will be seen by an inspection of Figs. 12 and 14.

A door opening 143, Fig. 1, is provided in each side wall. This opening has door posts 144 and 145 at each side thereof. These posts are channel shape in cross-section having their web portions turned toward each other and arranged transversely of the car and each has a wooden filler post 146 contained within the channel Figs. 12 and 14. Each of the posts 146 may, if desired, be provided with a rabbet adjacent the ends of the inner flange in which is secured a suitable finishing strip 147, see Figs. 12 and 14. The outer flange of the door post 144 is return bent as at 148, Fig. 12, for providing a channel for receiving the front edge of the flange of the door frame as will presently appear. The outer flange of the door post 145 is bent outwardly and rearwardly to form a keeper 149 for engaging the corresponding flange on the door frame as will be described later.

Suitable gusset plates 151 and 152, Figs. 1 and 12 to 15, are provided for each of the door posts at the corners formed by the junction of the door posts with the side plates and side sills, respectively, Fig. 2. The lower gussets 152 extend across the corner formed by the door posts and side sills and each comprises a triangular plate having an inwardly extending flange 153, Fig. 13, along its hypotenuse and a similar flange 1530 along its base which rests on the vertical flange 134 of the side sill. The vertical edge of each of these plates is opposite the vertical edge of the panel or plate to which they are attached and the gusset is welded to the plate so that when in position, the vertical edge of the gusset extends along the outer surface of the door post between the outer sheathing and post as indicated in Fig. 12. The flanges 153 and 1530 are foreshortened adjacent to the door post to permit the edge of the gusset to be inserted between the sheathing and door post, Fig. 13. The gussets 151 are secured across the corner formed by the door post and the side plate and are similar to the gussets 152 and are attached in substantially the same manner but are turned upside down.

The corners of the car body may be and preferably are provided with similar gussets 154, Fig. 2. The vertical edges of the gussets 154 are positioned between the vertical flange of the corner post and the reinforcing member and are welded in position as indicated in Figs. 16 and 17.

The upper edge of the sheathing and side posts extends upwardly on the inner side of the flange 135 of the side plate and is welded thereto.

The side posts are rigidly connected at their lower ends to the vertically extending flange 134 of the side sill in any suitable manner. In the form of the construction shown, in Figs. 6 and 7a, suitable brackets 120 are employed for this purpose. The web 137a and flange 137b of the side posts terminate at the upper edge of the flange 134 and the outer or offset portion 138, together with the adjacent sheathing extends downwardly on the outside of the side sill and is welded thereto. A bracket 120, Fig. 7a, U-shaped in cross-section, which has its web portion welded to the post 141, extends downwardly beneath the same along the inner side of the flanges 134 of the side sill 90, Figs. 6 and 7a, and has its outer enlarged flange welded thereto. The lower end of the bracket may be tapered downwardly at its lower end, that is, it is bevelled downwardly from its inner side at its lower end and terminates

above the fillet 155 extending along the angle formed by the vertical flange 134 and floor 6. Any other suitable type of bracket may be employed for this purpose.

In Figs. 27 and 28 a different type of bracket for securing the side posts to the side sills is shown. In this form of the construction, a triangular bracket or plate 156 having a flange 157 welded to one side of the side post, is employed. This bracket extends downwardly below the side post alongside the inner surface of the side sill flange 134 and is welded thereto. Gussets or reinforcing members 158 are employed for reinforcing the plates 156. Each of these reinforcing members or gussets 158 has a side or vertical flange 159, a top or horizontal flange 161 and an end flange 161a. The side or vertical flange 159 of the plate is welded to the downwardly extending body portion of the plate 156 and the end flange 161a is welded to the lower portion of the flange 157. This same construction is duplicated on the opposite side of each side post as indicated in Fig. 28.

The roof construction comprises a plurality of carlines 162, Figs. 6 and 10, and a roof member 163. The roof member 163 comprises a plurality of sheet metal plates 164, Fig. 1, that extend transversely of the car and are connected together in a manner similar to the plates forming the outer sheathing at the sides of the car. Except at the ends of the car, each plate 164 has one of its edges bent to Z-form to form the carlines. The width of the vertical portion 165, Fig. 11, of each carline gradually decreases toward the ends in order to form the curve for the roof, consequently, at their ends the flange portion 166 of the carline will be considerably widened, Figs. 11 and 26. The carlines are formed integral with the roof sheets or plates 164 and are preferably reinforced by angle bars 167 in a manner similar to that already described. The carlines are of such length that they are positioned between the vertical portions 160 of the side plates 132 and the body of the sheets 164 extends over the outer flange 136 of the side plates as shown more clearly in Figs. 10 and 26 of the drawings. The carlines are secured to the vertical portion 160 of the side plate by angle bars 168 which extend beneath the carlines and are welded to the lower edges of the carlines and the side plates 132. The plane edges of the roof sheets or plates are positioned in the offset of the adjacent sheet and are welded thereto in the manner already described. The front and rear ends of the roof member 163 are extended forwardly and rearwardly over the upper flange of the end plates 83 as shown in Fig. 11.

The roof sheets or sheet metal plates 164 of the roof member 163 are of the same width as the sheet metal plates 137 of the exterior side sheathing of the car and are so arranged that each carline 162, except those over the door openings, is in substantially the same vertical plane as two oppositely arranged side posts as shown in Figs. 2, 23 and 26 of the drawings, and are rigidly connected together. These members are of like contour in cross-section and have their flanges extending in the same direction. By means of this arrangement, all buffing stresses applied to the car will be transferred from one side of the car to the other through the side posts and carlines thereby permitting the use of thinner sheet metal plates for the siding.

If desired, suitable ladders 169 and 171, which

may also be constructed of pressed metal except for the rungs, are rigidly connected to the side and ends of the car as is usual in such constructions. Likewise, a suitable walk 172 is provided for the top of the car.

Suitable doors are also provided for each side of the car. The flange 134 between the door posts is notched or partially removed, Figs. 2 and 10, to accommodate the floor plate or threshold plate 173 which extends over the floor and between the door posts and has its outer edge bent downwardly as at 174 for providing a guide for the door 175. Suitable tracks are provided for supporting and guiding the door in its movement to open and closed position. The lower track comprises an angle member 176 which is adapted to be secured to the subframe or sub-sill 177 as by means of suitable gussets 178. The rollers for supporting the door are adapted to ride on this angular support and the roller mechanism has the usual guide for engaging the flange 176. Since this structure is old in the art, it is not shown. The upper end of the door is guided in its movement by a track 179 which is welded to the vertical flange 135 of the side plate and has its lower end turned outwardly and upwardly for engaging in a corresponding channel 181 formed by the edge of the vertical flange of the door frame 182. An angular member 183 extends outwardly and downwardly over the track 179 for protecting the same against the weather.

Numerous modifications may be made in the arrangement and the welding of the different parts. For instance, in Figs. 9, 18, 19 and 20 is shown a modified form of corner post construction. The form of the corner post shown in Fig. 9, for instance, differs from that shown in Fig. 8 in that the extension or flange portion 1190 of the reinforcing member 1150 does not extend rearwardly beyond the front edge of the side sheathing to which it is welded.

In the form of construction shown in Fig. 18, the corner post 88 is the same as that shown in Fig. 8 but the bracing or reinforcing member 115a is of a different form in that its edge 122a is flat and engages the outer end sheathing 126 extending along the inner side of said sheathing and is welded to the same at a plurality of points as shown by the arrows in Fig. 18. The inner edge of the flat section 122a extends partially behind the fillers or furrings 135.

In Fig. 19, the end sheet or plate 127 is extended outwardly beyond the furring or filler 135 and the edge 122b of the reinforcing member 115b is inserted between the lateral flange of the post 88a and the rearward extension of the sheet 127 and is welded thereto. The lateral edge 211 of the side flange of the corner post 88a is offset inwardly and engages the plate 127 to which it is welded as indicated by the arrows in Fig. 19.

In Fig. 20, the corner post 88b is formed as a continuation of the side sheathing 212 and the reinforcing member 115c is similar to that shown in Fig. 18 except that it is foreshortened so as not to come in contact with the filler or furring 135 and is welded to the sheet 212 as shown by the arrows.

In Fig. 21 is shown a modified form of one of the end posts 87a. In this form of construction, one of the feet as 89a is extended a sufficient distance to permit two welds instead of one, as indicated by the arrows in said figure, for connecting two sheets of the end sheathing.

The side posts may be attached to the side plate 132 in various ways and by divers means. In all of the figures, the side sheathing and side posts extend upwardly on the inner side of the vertical flange 135 of the side plates 132 and are welded thereto, Figs. 22 to 25.

In the modified form of the construction shown in Fig. 22, the inner flange 213 of the post 141 is extended alongside the vertical web portion 160 of the side plate and is bent to extend beneath the carline 162 to which it is rigidly secured as by being welded thereto.

In Fig. 23, the inner flange 214 of the angle member 142 is extended upwardly along the inner side of the vertical portion 160 of the side plates 132 and is bent beneath the carline 162 and rigidly secured to these parts as by welding.

In Fig. 24, a separate bracket 215 extends downwardly along the inner flange of the side posts 141 and is secured thereto. This bracket extends upwardly along the inner side of the vertical portion 160 of the side plates 132 and is bent inwardly beneath the carline 162 to which parts it is rigidly secured as by welding.

In Fig. 25, the flange 216 of the side post 141 extends upwardly along a portion only of the part 160 of the side plate 132 and a separate bracket 216 having one flange rigidly secured to the vertical portion 160 of the side plate and having its other flange extending beneath the carline 162 is welded thereto.

In Figs. 29 and 30 is shown a modified form of side sill and floor support. In this form of the construction, a pair of angle members 217 and 218, turned back to back, and welded together, are employed at each side of the car. The bar 218 has its horizontal flange 219 extending the full length of the horizontal flange 221 of the bar 217 and extends outwardly beyond the same a sufficient distance to receive the side posts 141. In this construction, the side posts 141 are secured to the angle 217 in such position that the outer sheathing 137 extends downwardly alongside the vertical portion 222 of the angle member 218 and is welded thereto. In this form of the construction, the fillet member 155 is between the angle member 217 and the outer sheathing between the side posts and the side and corner posts, suitable recesses being provided for accommodating the flanges of the side posts. In this construction, the floor 6 is supported on the horizontal flange 221 of the angle 217.

In fabricating the car body, the ends, sides and roof are constructed separately and then assembled on the underframe. The ends, sides, roof and doors are fabricated in horizontal position on jigs because of the convenience in welding.

In constructing the sides of the car, for instance, the sections of the side sheathing between the door posts and corner posts are fabricated as independent or separate units. Each sheathing section comprises a plurality of separate sheets or plates. Each plate first has its edge pressed to form the integral side post and then the plates are welded together as previously described. The door posts are placed in position between the side plates and side sills and welded together. The sheathing is then secured to the various framing members, including the door posts, top plate, and side sill, and is removably attached to temporary corner posts, and the integral side posts are fastened at top and bottom to the side plate and the side sill.

The roof and end sections are constructed in a similar manner. The corner posts are welded to

the outside sheathing of the end wall in fabricating the end wall.

After the side walls, end walls, roof and doors have been fabricated on the jigs and the angle members and subsills or subframe members have been attached, the parts are assembled on the underframe. In assembling the car body, the side walls are placed in position on the subframe with the bolster ends in the space formed by the angle members and the bottom flanges of the side sills and outer ends of the cross bearers and floor supports in the space formed by the flanges of the side sills and subsills. These bolster, cross bearers and floor support ends are welded in position as indicated in Figs. 2 and 3. The temporary corner posts are removed from the side sheathing. The end walls are then placed or slid in position with the ends of the side sheathing extending between the flange 113 of the corner post 88 and the flange 117 of the reinforcing member 115, Fig. 9, and the parts rigidly connected together by rivets 117 as shown, or by welding. In sliding the end walls in position to cause the side sheathing to slip in between the end post and the end post support, the auxiliary end sills 72 and brace members 76 of the end sill sections slide along on each side of the center sill. When in position, the end sills, auxiliary end sills and brace members are connected to the center sill by arc-welding as shown in Fig. 3. The top section is then placed in position and the parts rigidly secured together as by welding or rivets as previously described. The floor and inner sheathing and the like are then applied.

It will thus be seen that by the use of sheet metal and the extensive welding of the parts, the elements of the construction that are subjected to minimum stresses are not burdened with excess metal and those parts that are subjected to the greatest stresses may be built up to the desired or adequate strength, whereby a car of minimum weight and maximum strength is provided. The fabrication of the sides and ends, being done on horizontal jigs, the walls may be constructed and the car assembled at a minimum of time and expense.

It will thus be seen that when the parts are all assembled, a car is provided in which the super-structure and underframe are welded into a unitary structure.

The construction herein described is for the purpose of disclosing one form of the invention and is by way of example only and it is understood that the invention is not to be limited except by the prior art and the appended claims.

It is thought from the foregoing taken in connection with the accompanying drawings that the construction and operation of our device will be apparent to those skilled in the art, and that

changes in size, shape, proportion and details of construction may be made without departing from the spirit and scope of the appended claims.

We claim as our invention:

- 5 1. A side wall for a car body comprising a side plate, a side sill, and an outer sheathing having a door opening therein, door posts at each side of said opening secured to said side plate and side sill, said sheathing being composed of vertically
10 extending plates rigidly secured to said side plate and side sill, certain of said vertically extending plates having their vertical edges offset inwardly to form recesses and bent to form integral side posts, angle irons nested with said posts and
15 welded thereto to form reinforced side posts, the edges of adjacent vertically extending plates welded in said recesses to form a continuous outer sheathing with integral reinforced side posts, said vertically extending plates when assembled forming
20 a wall having a smooth outer surface and supported between its ends solely by said side plate, side sill, door posts and reinforced side posts.

2. In a railway car, side and end walls of sheet metal, sheet metal side and end plates, sheet metal side and end sills, sheet metal corner posts each comprising a flanged outer member having one flange extending longitudinally of the car and one extending transversely thereof, said
25 flanges being secured to said plates and sills, a reinforcing member extending diagonally across from one of said flanges to the other and having flanges parallel with the flanges of said outer member, said side and end walls being rigidly
30 secured to said plates and sills and having their vertical edges adjacent to said posts extending between the adjacent flanges of said corner posts and rigidly secured thereto.

3. In a railway car, side and end walls of sheet metal, sheet metal side and end plates, sheet metal side and end sills, sheet metal corner posts each comprising a flanged outer member having one flange extending longitudinally of the car and one extending transversely thereof, said flanges
35 being secured to said plates and sills, a reinforcing member extending diagonally across from one of said flanges to the other and having flanges parallel with the flanges of said outer member, said side and end walls being rigidly secured to
40 said plates and sills and having their vertical edges adjacent to said posts extending between the adjacent flanges of said corner posts and rigidly secured thereto, and a pair of filler members, the flanges of said reinforcing member being
45 offset for embracing two adjacent sides of said
50 filler members, respectively.

CERTIFICATE OF CORRECTION.

Patent No. 2,265,178.

December 9, 1941.

ALFRED C. LOHSE, ET AL.

It is hereby certified that error appears in the printed specification of the above numbered patent requiring correction as follows: Page 3, second column, line 17, after "flange" insert --removed--; page 6, second column, line 7, for "ocnstruction" read --construction--; and that the said Letters Patent should be read with this correction therein that the same may conform to the record of the case in the Patent Office.

Signed and sealed this 27th day of January, A. D. 1942.

Henry Van Arsdale,
(Seal) Acting Commissioner of Patents.
